J. S. NAERY.
FRICTION DRAFT GEAR FOR RAILWAY CARS.
APPLICATION FILED SEPT. 7, 1917.

Patented May 20, 1919.

UNITED STATES PATENT OFFICE.

JOHN S. NAERY, OF LA FAYETTE, INDIANA.

FRICITION DRAFT-GEAR FOR RAILWAY-CARS.

1,303,943.

Specification of Letters Patent. Patented May 20, 1919.

Application filed September 7, 1917. Serial No. 190,228.

To all whom it may concern:

Be it known that I, JOHN S. NAERY, a citizen of the United States, and residing at La Fayette, county of Tippecanoe, State of Indiana, have invented certain new and useful Improvements in Friction Draft-Gears for Railway-Cars, of which the following is a specification.

This invention relates to draft riggings for railroad cars and comprises an improvement in draft riggings of the friction type in which the draw bar of the car is engaged by friction devices which absorb the sudden shock caused in the coupling of cars and protect the framework and running gear from injury.

The object of the invention is to provide a draft rigging of this class which is simple and inexpensive to construct and apply to railroad cars, which renders unnecessary the heavy springs and friction blocks found on other devices of this description, and in which the ability of the apparatus to absorb shocks is directly proportional to the weight of the car.

The invention will be fully disclosed in the following description, taken in connection with the accompanying drawings, in which—

Fig. 1 is a top view of the apparatus part being broken away.

Fig. 2 is a section along the line 2—2 of Fig. 1;

Fig. 3 is a section along the line 3—3 of Fig. 1; and

Fig. 4 is a section of a modified form of friction device.

The car body is not shown nor the trucks supporting the same as these features are old and well known, but a portion of the car floor is indicated by the numeral 10 in the drawings and the truck bolster is indicated by 11. Directly above the truck bolster is the transverse body bolster 12 and the two bolsters are pivotally connected together by the center pin 13 in the usual manner.

The body and truck bolsters have center plates 14 and 15 respectively securely bolted thereto through each of which the center pin 13 passes, and these center plates instead of bearing against each other or against intermediate anti-friction devices as is usually the case, bear against the opposite faces of the friction plate or yoke 16 pivotally connected to the draw bar 17 at 18. Thus the

friction yoke 16 supports directly the weight of the car and it may only be moved by impacts against the coupler and draw bar which are of such magnitude as to overcome the great frictional resistance caused by the weight of the car pinching or clamping the friction yoke between the center plates 14 and 15.

The friction yoke 16 has two parallel arms, one of which passes on each side of the center pin 13 and each of the arms lies in a slot 19 in the truck bolster center plate 15 so that the yoke cannot become accidentally displaced.

As the yoke is held substantially longitudinally of the car at all times by the draw bar, while the truck bolster and center plate rotate as the car moves around curves, I have tapered the slot 19 toward the center from each side of the plate so that the yoke will have sufficient play. The forward end of the yoke 16 is forked, one arm extending over, and the other under the rear end of the draw bar 17. The pin 18 passes through each of these forks and through the draw bar, providing a substantial pivotal connection.

The draw bar extends to the end of the car between the usual sills or channels 20 and has the coupler 21 secured to the end thereof. A portion of the draw bar between the coupler 21 and the pivot 18 comprises a yoke within which the followers 22 and 23 are held. These followers have between them the heavy coil spring 24 which assists the friction yoke in absorbing shocks inasmuch as the cheek plates 25 secured to the sills 20 limit the motion of the followers in the usual manner, and insure that the spring 24 is compressed when the draw bar is moved in either direction.

In Fig. 4 I have shown a modification in which anti-friction rollers 26 are placed between the friction yoke and the two center plates in case it is desired to decrease the friction. It is apparent that the degree of resistance offered to the passage of the friction yoke between the center plate depends upon the weight of the car and its load. This is a very desirable feature inasmuch as the heavier the car is the greater the jar it is capable of giving and the greater the shock absorbing power should be.

When my invention is used the heavy shocks transmitted by switching or in train service, do not in any way damage the draft

sills or gear, or affect the loading, and a great saving in upkeep is made, as well as an original saving in installation over other devices of this character.

5 Having thus described the invention what is claimed as new and desired to be secured by Letters Patent is:

1. The combination with a railroad car having a body bolster and a truck having a 10 bolster, of a draft rigging including a slide- able member resting on the truck bolster and in turn supporting the body bolster whereby movement of the member is frictionally resisted by its contact with said bolsters.
- 15 2. The combination with a railroad car having a body bolster, a draft rigging and a truck having a bolster, of a member secured to the rear of said rigging resting on the truck bolster and in turn supporting the 20 body bolster whereby movement of the member is frictionally resisted by its contact with said bolsters.
- 25 3. The combination with a railroad car having a draft rigging including means to yieldingly resist movement thereof, of a member secured to said rigging and extend-

ing rearwardly between the body and truck bolsters and acting to transmit the weight of the car from the body to the truck bolster whereby movement of the member is frictionally resisted in proportion to the weight of the car. 30

4. The combination with a railroad car having transverse body and truck bolsters and a center pin pivotally securing them together, of a draft rigging therefor, comprising a draw bar, a yoke plate pivotally secured to said draw bar and having its arms extending between said bolsters on opposite sides of said center pin, said yoke plate being subjected to the direct weight of the car. 35

5. The combination with a railroad car having a transverse body bolster and a truck therefor having a bolster, of a draft rigging comprising a draw bar and an extension 40 plate secured thereto and extending between said body bolster and said truck bolster where it is subjected to the direct weight of the car and antifriction means between the extension plate and bolsters. 45

In testimony whereof I affix my signature. 50
JOHN S. NAERY.
